UNITED STATES PATENT OFFICE

2,636,648

WEIGH HOPPER

John N. Richardson, Port Washington, Wis., assignor to Modern Equipment Company, Port Washington, Wis., a corporation of Wisconsin

Application June 19, 1948, Serial No. 34,016

7 Claims. (Cl. 222—503)

1

This invention relates to improvements in weigh hoppers.

In foundries it is common practice to use weigh hoppers for the purpose of depositing a charge of predetermined weight into cupola charging buckets which, when they are in the loading pit, are positioned directly below said weigh hoppers. Certain charging buckets of recent design have been built with an elongated beam of box-like construction extending diametrically across the open upper portion thereof. In loading this type of bucket from the conventional type of weigh hopper, an appreciable amount of the charge will lodge on top of the cross-beam or roll off of said beam and drop exteriorly of the charging bucket. Any spilling of the charge as above described obviously results in waste and inefficiency.

It is therefore a general object of the invention to provide a weigh hopper which, when used to load a charging bucket, will direct all of the charge into the bucket.

A further object of the invention is to provide a weigh hopper which is formed with a central partition of predetermined thickness extending from one side of the hopper to the other.

A further object of the invention is to provide a weigh hopper wherein the partition is so disposed that when the hopper is used to load a charging bucket having a beam extending across the top thereof, the partition will be aligned with said beam and will prevent any appreciable amount of the charge from coming in contact therewith.

A further, more specific object of the invention is to provide a weigh hopper of the class described having a pair of swingable bottom doors and having a hollow partition within which the linkage for actuating said doors is mounted.

A further, more specific object of the invention is to provide a weigh hopper of the class described having a pair of swingable bottom doors each of which is supported by a pair of lugs pivotally mounted on the outside of the bucket, and each of which is provided with a centrally disposed lug which extends into the hollow partition and which is connected with the door actuating linkage therein.

A further object of the invention is to provide a weigh hopper of the class described wherein the swingable bottom doors thereof are connected to a safety linkage in a manner to cause simultaneous movement of both doors in response to actuation thereof by the actuating mechanism.

A further object of the invention is to provide a weigh hopper of the class described which is strong and durable, which is efficient in oper-

2

ation, and which is otherwise well adapted for the purposes described.

With the above and other objects in view, the invention consists of the improved weigh hopper, and all of its parts and combinations, as set forth in the claims, and all equivalents thereof.

In the accompanying drawing, wherein is disclosed one complete embodiment of the preferred form of the invention, and wherein the same reference numerals indicate the same parts in all of the views:

Fig. 1 is a side view of the improved weigh hopper;

Fig. 2 is a vertical sectional view of the improved weigh hopper taken along the line 2—2 of Fig. 3;

Fig. 3 is a plan view of the improved weigh hopper, parts being broken away to more clearly show structural details; and

Fig. 4 is a vertical sectional view taken along the line 4—4 of Fig. 1 and showing a portion of a charging bucket below the improved weigh hopper and in position to be loaded thereby.

Referring more particularly to Fig. 1 of the drawing, the numeral 5 indicates the improved weigh hopper having a rectangular body portion, and the numeral 6 indicates a pair of swingable bottom doors therefor. The hopper body is formed of a pair of substantially identical, spaced apart and parallel side walls 7 and 8 which are preferably rectangular in shape with the exception that the lower ends thereof taper downwardly as at 9 and 10 toward a central apex 11 (see Figs. 1 and 2). The walls 7 and 8 are connected at their side edges to a pair of parallel, preferably rectangular end walls 12 and 13. The upper ends of the walls 7, 8, 12 and 13 are preferably bent outwardly to form the marginal flange 14.

Extending between the central portions of the end walls 12 and 13 are a pair of spaced walls 15 and 16 which are substantially the same shape as, and are parallel with, the side walls 7 and 8. The walls 15 and 16 angle inwardly toward one another at the top thereof and join at a central apex 17. The walls 15 and 16 form a hollow partition which separates the hopper body 5 into two compartments.

The wall 13 is formed with a slot 44 extending upwardly from its lower edge, the side edges of said slot being coincident with the inner surfaces of the plates 12 and 13. The plate 12 is formed with a slot 45 extending upwardly from its lower edge, and this slot is of the same size as the slot 44 but positioned oppositely there-

from. The plate 12 is also formed with an aperture 46 in its upper portion in line with the slot 45.

The swingable bottom doors 6 are substantially identical in shape and each comprises a flat rectangular plate 18, having elongated arms or lugs 19 projecting upwardly, at preferably right angles from its ends. The arms 19 extend outside the walls 7 and 8 of the hopper, as shown in Figs. 3 and 4, and are pivotally connected to said walls at their upper ends in any suitable manner, as at 20, 21, 22 and 23. The pivots 20, 21, 22 and 23 are so positioned that when the doors 6 are closed, the plates 18 thereof are in engagement with the edges 9 and 10 of the walls 7, 8, 15 and 16 and so that when the doors are opened, they can swing to the dot and dash line position shown in Figs. 1 and 2.

The arms 19 are so formed and positioned that the axes of the coaxial pivot points 20 and 23, 20 and 21 and 22 are each in substantially the same vertical plane as the center of gravity of their corresponding doors 6. Therefore, the doors 6, when in their normal closed position and when not subject to a load, are stable and do not tend to move. However, when a load is placed in the hopper and on the inclined plates 18, the inclination of the plates causes the doors to tend to swing outwardly to release the load. When the load is released, the doors tend to swing back to their normal stable closed position.

Each of the doors 6 is formed with an upstanding lug 24 which is preferably positioned midway between the arms 19 thereof, and near the outer edge thereof. The lugs 24 project upwardly and are parallel with the walls 15 and 16. Since the lugs 24 are on the centerlines of the doors 6, they project between the walls 15 and 16 of the hopper body, as shown in Figs. 2 and 3.

Pivots mounted between the upper portions of the plates 15 and 16 near one side thereof, as on the pin 25, is a bell crank lever 26 having a relatively short arm 27 and a relatively long arm 28 extending at preferably a right angle thereto. Pivots connected to the arm 27 of the lever 26 is a shaft 29, which may be connected to any suitable source of reciprocating power such as a hydraulic ram (not shown). The shaft 29 projects through the aperture 46 of the plate 12. Pivots connected to the end of the arm 28 and depending downwardly therefrom is an elongated link 30. The lower end of the link 30 is pivotally connected, as at 31, to a pair of links 32 and 33, and the latter project upwardly and outwardly where they are pivotally connected to the upper ends of the lugs 24, as at 34 and 35. It is to be noted that lever 26, the links 30, 32 and 33, and the lugs 24, are all within the hollow partition formed by the walls 15 and 16.

In operation, referring to Fig. 2, outward movement of the shaft 29 causes counter-clockwise rotation of the lever 26 about the pin 25. This movement will cause an upward pull on link 30 which, in turn, will cause the links 32 and 33 to push upwardly and outwardly on the lugs 24, 65 thereby swinging the doors 6 outwardly to the dot and dash line positions of Figs. 1 and 2. Inward movement of the shaft 29 will return the mechanism to the full line position of Figs. 1 and 2.

A lever 36 is pivotally mounted intermediate its length as at 37 on the exterior of the wall 7. The lever 36 preferably extends in a vertical direction when the doors 6 are closed. Pivotally connected at one end to the lower end of the

lever 36, and pivotally connected at the other end to one of the arms 19 of one of the doors 6, as at 38, is a link 39. Pivotally connected to the upper end of the link 36 and pivotally connected to one of the arms 19 of the other door 6, as at 40, is a link 41. The safety linkage formed by the lever 36 and links 39 and 41 insures both of the doors 6 moving in unison and insures such movement inwardly or outwardly from the apex 11 at the same speed. Referring to Fig. 1, as the doors 6 swing outwardly toward the dot and dash line positions, the lever 36 is moved clockwise by the pull thereon from the links 39 and 41. Neither door 6 can move without the other door moving the same amount inwardly or outwardly.

The improved weigh hopper is particularly well adapted for use with cupola charging buckets having a box-like beam or similar member extending across the open top thereof. Fig. 4 shows a fragmentary vertical sectional view of the upper portion of a bucket 42 of this type.

The bucket 42 has an outwardly flanged open top and has a box-shaped beam 43 extending diametrically across said open top. It will be noted that the periphery of the top of the bucket 42 extends substantially outwardly of the side plates 7 and 8 of the improved weigh hopper. The improved weigh hopper is preferably so positioned with respect to the loading position of the charging bucket 42 that the hollow partition formed by the plates 15 and 16 is directly above and in alignment with the box-shaped beam 43 as is clear from Fig. 4. The plates 15 and 16 are preferably spaced apart a distance greater than the width of the beam 43 of the bucket 42.

It is apparent that all of the charge which is placed into the improved weigh hopper can be directed into the charging bucket 42 without any of the charge striking the beam 43 and rolling exteriorly of the bucket, and without any of the charge lodging on top of the beam 43.

It is to be noted that the doors when in closed position have the bottom plates 18 angled toward one another as shown by full lines in Fig. 2, to conform with the angle of the bottom edges 9 and 10. This arrangement, in conjunction with the disposition of the pivots 20, 21, 22 and 23, insures that the lowermost portions of the arcs of movement of the lowermost edges of the plates 18 are never substantially below the point 11 of Fig. 2. Thus, the bottom of the weigh hopper can be positioned relatively close to the top of the bucket to be filled, as in Fig. 4, and the doors can be swung to open position while the members are disposed in the position of Fig. 4 without the doors hitting the top of the bucket 42. By making it possible to position the weigh hopper close to the top of the bucket, spillage of the charge to the exterior is prevented.

The improved weigh hopper is provided with door operating mechanism which is composed of a minimum number of parts, and which, in addition, operates smoothly. The unique hollow partition not only provides a means for mounting the novel actuating linkage, but it also provides a cover for said linkage which prevents any portion of the charge from coming in contact with the linkage and thereby fouling it. The safety linkage insures that both doors operate simultaneously, thereby preventing jamming thereof.

Various changes and modifications may be made without departing from the spirit of the invention, and all of such changes are contem-

plated, as will come within the scope of the claims.

What I claim is:

1. A weigh hopper comprising a body having side walls, having an open top and an open bottom, a pair of swingable doors for said bottom, each of said doors being formed with a pair of parallel arms projecting upwardly at a right angle therefrom and pivotally connected to opposite sides of said hopper body, a lever pivotally mounted intermediate its length on one side wall of said hopper body between the adjacent arms of said doors, a link pivotally connecting one end of said lever with an arm of one of said doors, a link pivotally connecting the other end of said lever with an arm of the other of said doors, said links being of such length that one end of said lever is at all times positioned above the axis of pivotal movement of said lever and the other end of said lever is at all times positioned below said axis of pivotal movement; and means separate from said lever and links for opening said swingable doors.

2. A weigh hopper comprising a rectangular body having an open top and an open bottom, a pair of swingable doors for said bottom, a hollow vertical partition in said hopper extending between one pair of opposite sides thereof and positioned intermediate the other pair of opposite sides thereof, each of said swingable doors being formed on its inner surface with a lug which is adapted to project into said hollow partition, a bell crank lever pivotally mounted within said hollow partition for movement in a vertical plane, a vertically extending first link positioned within said partition and pivotally connected at its upper end with one arm of said bell crank lever, a second link pivotally connected at one end with the lower end of said first-mentioned link and extending upwardly and outwardly to a pivotal connection with the lug of one of said doors, a third link pivotally connected with the lower end of said first-mentioned link and extending upwardly and outwardly to a pivotal connection with the lug of the other of said doors, and means for connecting the other arm of said bell crank lever with a source of reciprocatory power.

3. A weigh hopper comprising a rectangular body having an open top and an open bottom, a pair of swingable doors for said bottom, a hollow vertical partition in said hopper extending between one pair of opposite sides thereof and positioned intermediate the other pair of opposite sides thereof, said partition having a closed top and open bottom and side portions, each of said swingable doors being formed on its inner surface with a lug which is adapted to project into said hollow partition, a bell crank lever pivotally mounted within said hollow partition for movement in a vertical plane, a vertically extending first link positioned within said partition and pivotally connected at its upper end with one arm of said bell crank lever, a second link pivotally connected at one end with the lower end of said first-mentioned link and extending upwardly and outwardly to a pivotal connection with the lug of one of said doors, a third link pivotally connected with the lower end of said first-mentioned link and extending upwardly and outwardly to a pivotal connection with the lug of the other of said doors, and means for connecting the other arm of said bell crank lever with a source of reciprocatory power.

4. A weigh hopper comprising a rectangular

body having an open top and an open bottom, a pair of swingable doors for said bottom, a hollow vertical partition in said hopper extending between one pair of opposite sides thereof and positioned intermediate the other pair of opposite sides thereof, each of said swingable doors being formed on its inner surface with a lug which is adapted to project into said hollow partition, a bell crank lever pivotally mounted within said hollow partition for movement in a vertical plane, a vertically extending first link positioned within said partition and pivotally connected at its upper end with one arm of said bell crank lever, a second link pivotally connected at one end with the lower end of said first-mentioned link and extending upwardly and outwardly to a pivotal connection with the lug of one of said doors, a third link pivotally connected with the lower end of said first-mentioned link and extending upwardly and outwardly to a pivotal connection with the lug of the other of said doors, means for connecting the other arm of said bell crank lever with a source of reciprocatory power, and safety linkage pivotally mounted on said hopper body and pivotally connected to each of said doors, said linkage being arranged to cause both of said doors to move simultaneously.

5. A weigh hopper comprising: a body having a pair of oppositely disposed sidewalls and having an open top and an open bottom, the lower edges of said opposite sidewalls being V-shaped; a pair of doors each having an inclined portion normally positioned in engagement with the V-shaped lower edges of said hopper sidewalls to close the open bottom of said hopper; and a pair of supporting arms projecting upwardly from each door and pivotally connected at their upper ends to said opposite hopper sidewalls at points spaced laterally outwardly from the apexes of the lower edges of said walls on the same side of said apexes as the corresponding door, said pivotal connections of the door supporting arms of each door with the hopper sidewalls being above and in substantially the same vertical plane as the center of gravity of said door when the latter is in its normal closed position, whereby said doors are in stable suspended condition when closed.

6. A weigh hopper for use in filling a bucket which has a vertical partition comprising: a body having a pair of oppositely disposed sidewalls and having an open top and an open bottom, the lower edges of said pair of opposite sidewalls being V-shaped; a hollow vertical partition extending transversely of said hopper body midway between said pair of sidewalls, the lower edge of said partition having substantial width to prevent material from lodging on top of the bucket partition; a pair of doors each having an inclined portion normally positioned in engagement with the V-shaped lower edges of said hopper sidewalls to close the open bottom of said hopper; a pair of supporting arms projecting upwardly from each door and pivotally connected at their upper ends to said opposite hopper sidewalls at points spaced laterally from the apexes of the lower edges of said walls on the same side of said apexes as the corresponding door, said pivotal connections of the door supporting arms of each door with the hopper sidewalls being above and in substantially the same vertical plane as the center of gravity of said door when the latter is in its normal closed position, whereby said doors are in stable suspended condition when closed; power operated actuating linkage in said hollow partition connected to said doors; and safety linkage

pivotedly mounted on said hopper body and pivotedly connected to each of said doors, said safety linkage being arranged to cause both of said doors to move simultaneously.

7. A weigh hopper comprising: a body having a pair of oppositely disposed sidewalls and having an open top and an open bottom, the lower edges of said opposite sidewalls being V-shaped; a hollow vertical partition in said hopper parallel with said sidewalls and midway therebetween; a pair of doors each having an inclined portion normally closing the open bottom of said hopper and positioned in engagement with the V-shaped lower edges of said hopper sidewalls; a pair of supporting arms projecting upwardly from each door and pivotedly connected at their upper ends to said opposite hopper sidewalls at points spaced laterally from the apexes of the lower edges of said walls, said pivotal connections of the door supporting arms of each door with the hopper 20

sidewalls being above and in substantially the same vertical plane as the center of gravity of said door when the latter is in its normal closed position, whereby said doors are in stable suspended condition when closed and power operated actuating linkage in said hollow partition connected to said doors.
